TANK FOR PETROLEUM OR OTHER LIQUIDS

Jean Peyrouze, Asnières, France

Application February 21, 1936, Serial No. 65,116
In France March 14, 1935

8 Claims. (Cl. 220—85)

For the storage of petroleum, gasoline, oils or other liquids use is ordinarily made of metal tanks, usually surface tanks, or of surface or underground masonry tanks.

Now, the former must support the total weight of the liquids they contain, they present serious risks of catching fire, and their high cost price, as well as the maintenance they necessitate constitute appreciable inconveniences particularly when important quantities of liquids are to be stored.

Concerning masonry tanks, surface or underground tanks, it is difficult, in the case of large capacities, to give them a sufficient and durable fluid-tightness, especially when they are to contain liquids such as those above mentioned.

The object of the present invention is to provide an improved underground tank, devised for avoiding all these inconveniences that is to say of simple and economical construction, and having a perfect fluid-tightness, even for the largest capacities.

This tank comprises a casing made of rustless metal, open at the top and bottom, the periphery of which fits against the vertical walls of a masonry chamber and the lower edge of which is immersed in a volume of water contained in the bottom of this chamber.

According to the present invention, the metal casing is constituted by a series of vertical strips the side edges of which are inwardly curved and secured against each other; these vertical strips are hung from the masonry chamber by connecting members which do not exert on these strips any restraining action, such for instance as pivoted and resilient members.

Owing to these arrangements, the casing is protected against any strain caused by expansions and contractions and it can be constructed of very thin sheet metal, consequently it is light and economical.

In fact, the curved edges of the sheet metal plates, which alone do not bear against the masonry wall, can easily become distorted by variation of their radius of curvature, which is chosen sufficiently large, for following the expansions and contractions of the metal in the peripheral direction, and the suspension members allow the metal to freely expand and contract in the vertical direction, because the pressure of the sheet metal plates against the masonry is slight owing to the hydrostatic back pressure and because the nature of the suspension members allows the vertical tensions to

approximately balance each other at all suspension points.

The accompanying drawings, given by way of example only, illustrates two embodiments of the invention.

Fig. 1 is a vertical section made according to line I—I of Fig. 2, showing the first embodiment.

Fig. 2 is a horizontal section made according to line II—II of Fig. 1.

Fig. 3 is a partial horizontal section, on an enlarged scale, at a joint of the casing.

Fig. 4 is a vertical section of a drawing up device.

Fig. 5 is a vertical section of the second embodiment.

Fig. 6 is a partial vertical section, on an enlarged scale, at a point of suspension.

Fig. 7 is a perspective view of a suspension device.

In Figs. 1 to 3, 1 designates an underground chamber or masonry pit, the complete water-tightness of which is not indispensable.

In this pit 1 is arranged a fluid-tight bottomless casing 2, made for instance of rustless steel, and supported at a certain distance *h* above the bottom of the pit 1.

It is assumed, in this example, that the pit 1 and casing 2 have cylindrical shapes, but these shapes although generally preferred for the convenience of construction, are not of course in any way compulsory, and they can be modified in any suitable manner according to the particular cases contemplated.

The bottom of the pit 1 contains a layer of water E in which the base of the casing 2 is immersed.

The liquid P to be stored is poured into the casing 2. It floats on the water E, whilst the latter rises in the interstices comprised between the casing and the inner wall of pit 1.

This arrangement is adapted to avoid any contact between the liquid P and the masonry, and to ensure the storing of this liquid P in a space which can be rendered perfectly fluid-tight, this space being bounded, on the one hand, by the casing 2 and on the other hand, by the hydraulic seal at its base.

The pit 1 is closed at its upper part by a vault which can communicate with the atmosphere through an inspection conduit 4.

The casing 2 is constituted by longitudinal strips of any suitable width (this width can be limited only by rolling possibilities) and these strips are assembled as follows:

Their side edges **2a**, radially disposed at the inner periphery of the casing, are inwardly curved, and the adjacent edges of two adjacent strips are fitted one against the other on a certain width and assembled preferably by means of one or more continuous welds such as **2b**.

A perfectly fluid-tight joint is thus obtained, in which the means used for the assemblage are stressed in much more satisfactory condi-

10 tions than in ordinary tanks: the pressure of the liquid presses in fact the edges **2a** one against the other and compresses the assembling means **2b** instead of causing them to be subjected to a tensile or shearing stress, as is 15 usually the case.

On the other hand, the edges **2a** are joined to the portions of strips **2** which are pressed against the pit, by arcuate sections **2c** of large radius, which allow the casing to freely expand 20 or contract without the metal being subjected from this fact to supplementary stresses: in fact, owing to the arcuate sections **2c**, these expansions or contractions simply produce radial displacements of the edges **2a** in the direction of the arrow **F**, or in reverse direction.

The dimensions of the whole are such that, for the maximum contraction contemplated, the casing preserves the arrangement illustrated and remains pressed against the inner wall of the 30 pit, so as to always be stressed in the conditions described.

This casing is freely hung in the pit by means so devised that they do not exert any stress on the metal. In the example under consideration, 35 these means consist in hooks **5** from which the casing is hung through the medium of rings **6** secured to its upper edge.

The casing can be very easily fitted in position on the spot by separately hanging the 40 wound strips from the hooks **5**, by unwinding these strips and assembling them by their edges according to the arrangement described.

Under the pressure of the liquid **P** stored in the tank, the water **E** which ensures fluid-tightness 45 at the base of the casing rises, about this casing, in the empty spaces **7** existing between the arcuate sections **2c** and the inner wall of the pit **1**.

This water has in particular for effect to balance 50 the internal pressure on the arcuate sections **2c**, and to avoid the latter being distorted.

It is to be noted that, except in the case of important water leakage, the variations of level of the hydraulic seal remain very small, whatever 55 may be those of the level of the liquid **P**, considering the reduced volume of the spaces **7** enclosing the water columns balancing the pressure of this liquid **P**.

The plant is completed by the following devices:

60 Adjacent to the tank is provided a pumping chamber, in which are arranged two reversible sucking and forcing pumps, viz: a pump **8** for supplying and evacuating the liquid **P**, and a pump **9** adapted to compensate the leakage of the water **E** and to maintain the hydraulic seal at the required level, these two pumps being connected to suitably arranged pipe lines provided with a suitable gate valve system.

70 The water pump **9** can be automatically started and stopped by a manometric gauge or float device, for maintaining constant the level of the hydraulic seal.

The whole is preferably so devised that this 75 level of the hydraulic seal varies within limits

as narrow as possible, and the orifice of the conduit **10** connecting the pump **8** to the tank is at a level **h₁** as low as possible above the level of the hydraulic seal, so that nearly the totality of the liquid **P** contained in the tank can be 5 taken up by pump **8**. This level **h₁** must however be sufficient in order that the pumping should not risk causing water priming into conduit **10**.

For avoiding this inconvenience, the conduit 10 **10** can be caused to open (Fig. 4) in a small auxiliary vat **11** the edge of which is at a level **h₂** above the water plane. The section of this vat relatively large compared to that of conduit **10**, is adapted to avoid water priming upon 15 pumping, and allows of considerably lowering the level **h₂**. The orifice of conduit **10** is located, above the bottom of vat **11**, at a level **h₃** sufficient for preventing water from being sucked into this conduit **10** in case water should 20 accidentally enter vat **11**. The evacuation of this water can be ensured by a pump and a conduit **12**, eventually in an automatic manner, by means of a constant level device.

Fig. 5 shows a modification which differs from 25 the tank described with reference to Figs. 1 and 2 in that the masonry pit **13** is of annular shape, its central portion being occupied by a pillar **14** within which are provided a chamber 30 **15** for the petroleum pump **8** and water pump **9** and a conduit **16** for a water pipe **17**, a petroleum pipe **18** and an air pipe **19**. The metal casing **2** is constructed as previously described.

Each sheet metal strip is hung from a bracket 35 **20** (Figs. 6 and 7) sealed in the masonry, through the medium of a cross member **21** connected to the upper edge of said strip by a plurality of rings **22**, and to the bracket **20** by a screw-threaded rod **23** pivoted at **24** on the 40 middle portion of this cross member and bearing on the bracket through nuts **25**. The upper edge of the sheet metal strip is preferably reinforced by folding it or by a sheet metal band secured in position. The rings **22** freely pass through holes 45 formed in the cross member **21** and in the upper edge of the sheet metal strip; they are of relatively large diameter so that they resiliently distort under the weight of the strip and that the suspension stresses are nearly uniformly distributed on the strip and on the cross member 50 **21**. The suspension members of the casing have not been shown in Fig. 5, except at the place of the vertical section.

The central pillar is also covered with a metal 55 casing **2d** devised in a similar manner.

It is to be understood that the details of construction described above have been given solely by way of example, and it will be easy, without departing from the scope of the invention to make numerous modifications therein, particularly concerning the arrangement of the pit and fluid-tight casing, the means for absorbing the stresses exerted on these two elements, the pumping device, etc.

I claim:

1. In a tank for petroleum or other liquids, the combination of a masonry pit provided with a bottom, a radially extensible casing, made of rustless metal, vertically placed within this pit, 70 in contact with the vertical walls of the latter, and open at the top and bottom, means for hanging this casing within said pit so that its lower edge should be situated above the bottom of this pit, and a hydraulic seal in the bottom of 75

- said pit and in which is immersed the lower edge of said casing.
2. A tank for petroleum or other liquids, as claimed in claim 1, in which said casing, hung within said pit, is composed of vertical strips placed side by side, and the two vertical edges of which are inwardly curved, the adjacent strips being connected together by welding their adjacent vertical edges.
- 10 3. A tank for petroleum or other liquids, as claimed in claim 1, in which said casing, hung within said pit, is composed of vertical strips placed side by side and the two vertical edges of which are inwardly curved, each of the strips being joined at its vertical curved edges by arcuate sections having a large radius of curvature, the adjacent strips being connected together by welding their adjacent vertical edges.
4. A tank for petroleum or other liquids, as 20 claimed in claim 1, in which a tube for evacuating and introducing petroleum opens in the bottom of said pit and above the level of said hydraulic seal, and another tube, for the admission of the liquid of said hydraulic seal, opens 25 in said pit below the level of this hydraulic seal, and a pumping device for each of said tubes.
5. A tank for petroleum or other liquids, as claimed in claim 1, in which a tube for the discharge and admission of petroleum opens in the 30 bottom of a vat, this vat being placed on the bottom of said pit and having upper edges placed above the level of said hydraulic seal, and another tube, for the admission of the liquid of said hydraulic seal, opens in said pit, 35 below the level of this hydraulic seal, and a pumping device for each of said tubes.
6. A tank for petroleum or other liquids, as claimed in claim 1, in which a tube for the discharge and admission of petroleum opens in the bottom of a vat, this vat being placed on the bottom of said pit and having upper edges placed above the level of said hydraulic seal, and another tube, for the admission of the liquid of said hydraulic seal, opens in said pit, below the level of this hydraulic seal, and a pumping device for each of said tubes.
7. A tank for petroleum or other liquids, as claimed in claim 1, in which said casing is composed of vertical strips placed side by side, 15 means for hanging this casing within said pit and having rings threaded in holes formed in the upper edge of each of said vertical strips, horizontal cross members to which said rings are attached, brackets sealed in the vertical wall 20 of said pit, above said casing, and means for attaching each of said cross members to one of said brackets.
8. A tank for petroleum or other liquids, as claimed in claim 1, having a central column 25 made of masonry and devised for connecting the bottom of said pit to a vault covering the latter, a tube for the discharge and admission of petroleum, opening in the bottom of said pit and above the level of said hydraulic seal, another 30 tube for the admission of the liquid of said hydraulic seal, a pumping device for each of said tubes, this pumping device being arranged in a chamber provided within said central column and terminated at the top in a conduit adapted 35 to contain pipe lines extending from said pumping devices.

JEAN PEYROUZE.
